UNITED STATES PATENT OFFICE.

LOUIS A. CASGRAIN, OF WINCHESTER, MASSACHUSETTS, ASSIGNOR TO
UNITED SHOE MACHINERY COMPANY, OF PATERSON, NEW JERSEY,
AND BOSTON, MASSACHUSETTS, A CORPORATION OF NEW JERSEY.

NURLING-MACHINE.

SPECIFICATION forming part of Letters Patent No. 768,560, dated August 23, 1904.

Application filed December 31, 1902. Serial No. 137,285. (No model.)

To all whom it may concern:

Be it known that I, LOUIS A. CASGRAIN, a citizen of the United States, residing at Winchester, in the county of Middlesex and State of Massachusetts, have invented an Improvement 5 in Nurling-Machines, of which the following description, in connection with the accompanying drawings, is a specification, like characters on the drawings representing like parts.

This invention has for its object the production of a novel machine for operating on leather or other compressible stock. The machine contains as one of its members a tool 15 that may, among other uses, be made to nurl portions of the sole of a boot or shoe where the sole may have been somewhat defaced during the operation of securing the sole to the upper.

The machine and tool herein to be described may be used to advantage in the treatment of articles of leather or for nurling leather used for any purpose.

The tool herein shown is of circular form 25 and is adapted to roll or travel over the leather or stock to be treated, and while in contact with the stock the tool has imparted to it rapid percussional impulses, effected, preferably, by a series of blows delivered in rapid succession 30 by a revoluble hammer acting on a tool-carrier. The impulses thus transmitted to the stock are of high frequency. For the best results the tool will remain in contact with the stock being treated, and as the tool travels 35 over the stock the rapid percussional impulses result in subjecting the stock to rapid variations in pressure in the line of contact of the tool with the stock, such variations acting to compress and consolidate the stock acted upon 40 by the tool.

A patent of the United States, No. 693,686, granted to me February 18, 1902, shows and describes a machine for cutting openings in a sole, driving fastenings in the openings, and 45 then closing the openings to conceal the fastenings. My studies, aiming to improve the appearance of the sole which had been operated on by the machine described in said pat-

ent, resulted in the production of the machine and tool forming the subject of this invention, and by its use I have demonstrated that the openings referred to as having been made in the sole may be so firmly closed that the lines of cut are substantially obliterated. 50

The tool used herein is represented as a 55 roller or annulus having a series of peripheral teeth or projections that serve to nurl the stock. This invention is not, however, limited to this character of tool nor to the particular shape shown for the periphery of 60 the tool, and the teeth or projections may of course be varied in size and shape according to the design of nurling desired for the stock.

The rolling-tool will preferably be rotated solely by the moving stock and will preferably be so sustained as to be self-adapting to 65 the surface of the stock whether plane or curved.

A tool actuated as described may be used to great advantage on leather employed in 70 harness and other articles where nurling is desirable or where it is desired to somewhat harden or finish a portion of the stock by a series of rapid percussional impulses effected by a succession of rapid blows. 75

Figure 1 in side elevation represents a nurling-machine embodying my invention in one of the best forms now known to me. Fig. 2 is a detail of the mechanism for sustaining and operating the stock-support. Fig. 2^a is 80 an enlarged detail showing in section part of the tool-carrier and the tool acting on the surface of stock, the tool being in upright position. Fig. 2^b is a similar view showing the tool in an inclined position. Fig. 3 is a side 85 elevation of the upper part of the machine shown in Fig. 1, on a larger scale, showing the face-plate, the hammer, the die, and its carrier in section. Fig. 4 is a detail of the spindle-holder and the rear side of the revolving hammer. Fig. 4^a is a detail showing the clamping-block detached and the stud therein. Fig. 5 is a view of the upper portion of the front part of the machine. Fig. 6 is a section on the line α , Fig. 3, the stock- 90 support being omitted. Fig. 7 is a periph-

eral view of one form of tool. Fig. 8 shows a piece of stock portions of which have been operated upon by the nurling-surface and portions of which are in the condition in which it was left by the machine shown in said Letters Patent. Figs. 9 and 10 are enlarged sectional details of the lower end of a modified form of tool-carrier and tool, the latter being shown in different positions to illustrate the adaptability of the tool to the plane of the surface of the stock. Fig. 11 is a sectional detail in the line α' , Fig. 9.

The frame consists of a column A, having feet A' to rest upon the floor. The upper end 15 of the column sustains an arm A^x, shaped to receive a shaft A², provided with fast and loose pulleys A³ A⁴, that may be rotated by a belt A⁵ from any suitable source of power. The machine is started and stopped in usual 20 manner by a belt-shipper M.

The shaft A² is threaded at B (see Fig. 3) and is provided with a worm B'. The worm engages a worm-toothed gear B², fast on the upper end of a shaft B³, extended through a 25 bore in an upward extension B^x of a block B⁴, interposed between the front, or the right-hand end viewing Fig. 3, of the arm A^x and the face-plate B⁵, connected with the frame by bolts C. The lower end of the block B⁴ has 30 a depending hollow boss C', that serves as a bearing for the shaft B³, the threaded lower end of which is extended therethrough and receives upon it a toothed gear C². The boss C' is embraced by the split hub of a clamping-block C³, (shown detached in Fig. 4^a.) This block is held in adjusted position on the boss by a clamp-screw C⁴ and is bored to receive a headed stud-screw D, threaded at its lower 35 end to receive upon it a toothed gear D' and a feed-wheel D², having, preferably, a frictional surface D³. The rotation of the feed-wheel is effected by the shaft A² through the shaft B³ and the gears described. The inner side of the face-plate B⁵ has a guideway in 40 which is entered loosely a tool-carrier E², one side of which contacts with the face of the block B⁴.

The shaft A² carries a hammer presenting an irregular acting face adapted in the rotation of said shaft to impart to the tool-carrier a succession of rapid blows. For the best results the friction between the rapidly-rotating hammer and the tool-carrier should be reduced to the minimum, and to provide for this 50 in one of the best forms now known to me I have represented the hammer as comprising a block D⁴, having a series of rollers D⁵ sustained on spindles E; but this invention is not limited to the use of the particular form of 55 hammer shown, as my invention is broad enough to cover any form of hammer that will impart to the tool-carrier a succession of rapid blows. To reduce the friction between the spindles E and the rollers D⁵, surrounding 60 them, each spindle has been provided with a

hole for the reception of a wick α' , the free end of which enters an oil-chamber α' in the block D⁴. This block has a hole α^2 , through which oil may be supplied to the chamber α' . The spout of the oil-can used to supply oil to 70 chamber α' may be passed into a hole α in the face-plate B⁵. The spindles E are secured in position by a locking device E', (shown best in Fig. 4 as a plate,) having a series of projections 2, each of which enters a notch at the 75 side of one of the spindles near its inner end. By turning the locking device the projections 2 may be disengaged from the notches of the spindles, and the spindles may be withdrawn.

The lower end of the tool-carrier is provided with a tool-sustainer b, the upper side of which is convexed or crowning, (see Figs. 2^a and 2^b,) the under side being concaved, the line of the arc representing the concavity being struck from a center 5 (see Figs. 2^a and 2^b) below the tool-sustainer and the periphery of the tool. The tool b' is shown as a roller made as a ring convexed internally, viewing the same in cross-section. The periphery of the tool that contacts with the stock is represented (see Fig. 7) as having a series of teeth or projections, (shown as substantially parallel and of different lengths.) The tool shown will outline on the stock a waved line of nurling. The line of nurling not only obliterates 90 defacing-marks on the stock made in the operation of inserting fastenings, but also produces a line of ornamentation, and the stock in the line acted upon by the tool is compressed and consolidated. The particular configuration or design for the surface of the nurling-tool is of course not an essential part of this invention, and it will be understood that the acting face of the tool may be made to correspond with the work to be done or 100 the design it is desired to present on the stock. The tool b' surrounds loosely the tool-sustainer b and is free to travel thereabout when caused so to do by the movement of the stock in contact with the tool. When the tool in use is in contact with the stock, (see Fig. 2^a,) the convexed inner side of the tool is made to take a bearing against the concaved under side 10 of the tool-sustainer b, and preferably at this time the interior of the tool is substantially out of contact 110 with the convexed upper side of said sustainer. Fig. 2^a shows the tool in contact with stock having its surface parallel with the longitudinal axis of the tool-sustainer, and Fig. 2^b shows the top of the stock as occupying a position at an angle to said longitudinal axis. In each figure it will be seen that the tool is free to change its position in the direction of the length of said tool-sustainer, and yet the periphery of the tool bears in like manner on 120 the surface of the stock. The upper portion of the tool shown in Figs. 2^a and 2^b, or that portion above the sustainer b, is moved by change of position of the surface of the stock, and in this way the pressure of the periphery 130

of the tool is uniform and just the same whatever the position of the surface of the stock with relation to the longitudinal axis of the sustainer b . Supporting the tool in such manner that it may readily adjust itself to variations in the surface of the stock and the provision of rotating the tool by the stock and not positively by mechanism are important features of this invention. To insure the greatest perfection in the nurling, the tool should bear constantly on the stock while the machine is in operation. This contact may be insured by a spring F , interposed between the tool-carrier and the pin F' . The spring prevents the tool from leaving the stock between the successive blows of high frequency transmitted by the hammer through the tool-carrier. The pin F' , extended through a hole 4^x in the tool-carrier and entering a hole in block B^4 , serves to limit the descent of the tool-carrier under the action of spring F when the stock is removed from contact with the tool. The removal of the pin enables the tool-carrier to be taken out of the machine. The stock, herein illustrated as part of a shoe, will be sustained on an arm G , forming part of a stock-support, said arm having, preferably, a button 6 . The lower end of said arm has a split hub that receives clamping-screws 7 , by which to clamp said hub to an elongated sleeve G' , that surrounds loosely the upper end of a rod G^2 , free to slide vertically in a bearing G^4 , sustained by the column. Below the bearing G^4 rod G^2 is surrounded by a strong spring H , whose upper end contacts with the interior of a hollow weight G^5 , clamped on said rod by a clamping-screw 8 . The lower end of the spring H rests on an adjustable support H' , (shown as a nut applied to the threaded part 9 of a vertically-movable sleeve H^2 , that constitutes a bearing in which the lower end of the rod G^2 is free to slide.) The extremity of said rod has a stop 10^x to limit the upward movement of the rod G^2 by the spring H . The lower end of the sleeve has pins 12 , over which fit links 13 , and the opposite ends of said links embrace a pin 14 , carried by the upper end of a lever or treadle H^6 , pivoted at H^6 on an ear H^7 , extended from the frame. The lever has a stop 15 , which limits the downward movement of the rod G^2 and determines the position of the lever and stock-support when the machine is not in operation. When the machine is in operation, the operator keeps his foot upon the outer end of the treadle H^6 , holding the rod G^2 , through the spring H , yieldingly in elevated position, forcing the stock on the stock-support against the tool b' and holding the upper end of tool-carrier E^2 in the path of movement of the hammer. The weight G^5 gives to the stock-support the character of an anvil and prevents undue yielding of the support under the stroke of the hammer. The weight also on account of its inertia prevents

the stock-support rising between the rapid consecutive strokes of the hammer on the tool-carrier. The weight may be changed when desired and a lighter or heavier weight substituted, according to the speed at which the rotating hammer is run. The more rapid the blows of the hammer on the tool-carrier the more rapid will be the percussional impulses of the nurling-roller on the stock, and the more rapid the strokes of the hammer the lighter should be the weight, and vice versa.

In operation let it be supposed that the shaft A^2 and the hammer are being rotated at a very rapid speed, preferably a speed at which the hammer will strike the upper end of the tool-carrier from six to seven thousand blows a minute. The operator having applied the stock to the stock-support, as shown in Fig. 1, elevates the stock-support, presses the stock against the tool b' , raises the tool-carrier and places its upper end in the path of movement of the hammers that they may strike the tool-carrier a series of blows in rapid succession, enabling the tool b' , in contact with the stock, to respond to the hammer-blows and impart to the stock blows of high frequency or percussional impulses of great frequency. These blows cause the tool to knurl the stock and obliterate the marks made in inserting fastenings. While this is being done the work is held by the operator against the feed-wheel D^2 , which serves also the purpose of an edge-gage to determine the distance of the nurling from the edge of the stock.

The machine herein described is preferably made to act on the stock, if a shoe, in substantially the last operation of finishing the shoe after the sole has been leveled and buffed and preferably after the application to the buffed sole of usual dressing. I have found in practice that the extremely rapid succession of blows and the variations in the pressure of the tool on the stock over which it rolls cause the tool to clean itself from any foreign matter taken from the stock and adhering to the tool, and consequently the toothed periphery of said tool free from any adhering particles of stock may be run from the blackened shank of a sole onto the lighter-colored fore part without soiling the latter. It is unnecessary to heat the roller, as usually required in this class of work.

By the term "tool" I intend to include any device which may be used, as recited, for the purpose of nurling, embossing, compacting, or finishing portions of the stock.

Referring to the modification Figs. 9, 10, and 11, the tool b'^x surrounds loosely the tool-sustainer b^x , shown as a stud held in a throat cut in the lower end of the tool-carrier E^{2x} . The tool-sustainer has an annular projection 4 extended therefrom that sustains the tool in its rotation with the stock and permits the tool to move longitudinally of the tool-sus-

tainer when the surface of the stock acted upon by the tool varies so as to stand in a plane not parallel with the longitudinal axis of said sustainer.

- 5 The revolving hammer constitutes a constantly-moving means to cause the tool when in contact with the stock to impart to the latter percussional impulses of high frequency. When the stock is removed from contact with the tool, the hammers cease to strike the tool-carrier, and the tool becomes inoperative. By the term "percussional impulses" I mean a rythmical action of high frequency produced mechanically and setting up in the device 10 15 20 25 30 35 40 45 50 55 60 65 70 75 80 85 90 95 100 105 110 115 120 125 130
- acted upon a pulsatory or extremely rapid movement, and the best way now known to me for imparting this movement is by a series of rapid blows imparted by a revolving hammer; but this invention is obviously not to be limited to the mechanical embodiment herein shown and described.
- Having fully described my invention, what I claim as new, and desire to secure by Letters Patent, is—
1. In a machine of the class described, a leather-working tool, and means for imparting to said tool while in contact with the stock a succession of rapid blows.
  2. In a machine of the class described, a leather-working tool continuously in engagement with the stock, and means for imparting to the stock through said tool a succession of percussional impulses of high frequency in a direction approximately perpendicular to the plane of the face of the stock.
  3. In a machine of the class described, a leather-working tool, and means for imparting to said tool a succession of rapid blows when said tool is in contact with the stock, said means being arranged and constructed to cease actuating the tool when the tool is out of contact with the stock.
  4. In a machine of the class described, a leather-working tool, means for imparting to said tool a succession of rapid blows, and means for rendering said tool inoperative when the stock is withdrawn from position to be operated upon.
  5. In a machine of the class described, a rotary tool adapted to bear on the face of stock, a carrier therefor, and means to impart to said carrier percussional impulses of high frequency while the tool is rotated by the stock.
  6. In a machine of the class described, a tool normally in contact with the stock, and means to vary at rapidly-succeeding intervals while the tool is in contact with the stock the degree of pressure of said tool on the stock.
  7. In a machine of the class described, a tool-carrier, a tool rotatable only by the stock with which it contacts, and means to impart to said tool while in contact with the stock a series of blows in rapid succession.
  8. In a machine of the class described, a stock-support, a rotary tool to engage and

travel over the face of the stock, and means to effect rapid relative movement of the stock-support and tool toward and from each other to subject the stock to a succession of rapid blows.

9. In a machine of the class described, a rotatable tool to bear on the face of stock, and means for sustaining said tool so that it may maintain continuous contact with the moving stock whatever the plane occupied by the face 70 75 80 85 90 95 100 105 110 115 120 125 130

10. In a machine of the class described, an annular tool interiorly convexed in cross-section, and a tool-sustainer concaved at its under side to constitute a seat for said tool when the tool is in contact with the stock.

11. In a machine of the class described, a tool-sustainer shaped at its under side to present a concaved arc, and a surrounding ring-like tool interiorly convex in cross-section, the arc at the under side of the tool-sustainer being struck from a center below the periphery of the tool when in working position on the sustainer.

12. In a machine of the class described, a tool-carrier and tool, means for sustaining said carrier and tool normally in inoperative position, said parts being arranged to be put into operative position by the stock, and a continually-moving device to coact with said tool-carrier and cause the stock to receive a series of percussional impulses of high frequency when said carrier is placed by the stock in the path of said continually-moving device.

13. In a machine of the class described, a tool, and a tool-carrier having a tool-sustainer encircled by said tool, the tool being free to rotate about the sustainer and to be moved longitudinally with relation to said sustainer as the tool is moved by the stock.

14. In a machine of the class described, a tool adapted to bear on the stock, a tool-carrier, hammer mechanism to strike said tool-carrier a series of blows in rapid succession when the tool is in contact with the stock, and means for feeding the stock.

15. In a machine of the class described, a stock-support, a rotary tool adapted to engage the stock, means for imparting to said tool a succession of rapid blows, and a weight to enable the stock-support to move more sluggish than the tool.

16. In a machine of the class described, a rotatable hammer, means to rotate said hammer, a carrier movable relatively to said hammer provided with a leather-working tool, means to arrest said carrier in inoperative position with relation to said hammer, said carrier being put into operative position by the pressure of the stock against said tool.

17. In a nurling-machine, a carrier having a tool-sustainer, a tool loosely mounted on and rotatable freely about said sustainer by the action of the stock against said tool, and means to impart to said carrier and tool rapid move-

ment in a direction approximately perpendicular to the surface of the stock acted upon by said tool.

18. A stock-support, a leather-working tool, means to cause the stock to be clamped yieldingly between said stock-support and tool, means to change rapidly the relative positions of said tool and stock-support to cause the tool to deliver a series of blows at rapid intervals to the stock, and a weight to enable the stock-support to move more sluggishly than the said tool.

19. In a machine of the class described, a leather-working tool, actuating mechanism for causing said tool to engage and act upon the stock, and means acting automatically for causing the movements of the leather-working tool to be discontinued when the stock is not in position to be operated upon.

20. In a machine of the class described, a leather-working tool, actuating mechanism for causing said tool to engage and act upon the stock, and automatic means for causing the operation of the tool to be discontinued, without interrupting the operation of the actuating mechanism, when the stock is not in position to be operated upon.

21. In a machine of the class described, an operating-tool normally in continuous engagement with the work, actuating mechanism therefor, and means acting automatically, when the stock is disengaged from the operating-tool, to cause the movements of the tool to be discontinued without interrupting the operation of the actuating mechanism.

22. In a machine of the class described, an actuator, and a tool arranged to be moved

into operative relation to the actuator when the work is presented thereto, said tool being movable out of operative relation to its actuator when the work is withdrawn.

23. In a machine of the class described, a tool-carrier and tool, means for sustaining said carrier and tool, said parts being arranged to go automatically into inoperative position upon removal of the stock from the tool, and a continually-moving device to contact with said tool-carrier and cause the stock to receive a series of percussional impulses of high frequency whenever the tool-carrier is in operative position.

24. In a machine of the class described, a tool, and a tool-carrier having a tool-sustainer encircled by said tool, the tool being free to rotate about the sustainer and to move by a tilting longitudinal movement with relation to said sustainer as the tool is moved by the stock.

25. In a machine of the class described, a tool, a tool-carrier and hammering device, and means for sustaining said tool and carrier so that the tool-carrier tends to move automatically out of the range of the hammering device, and said carrier is moved into the range thereof by the stock presented to the tool.

In testimony whereof I have signed my name to this specification in the presence of two subscribing witnesses.

LOUIS A. CASGRAIN.
